UNITED STATES PATENT OFFICE.

BARNET NEWLAND, OF NEW YORK, N. Y.

DESIGN FOR A LOOP FOR LIGHTING FIXTURES.

61,375.

Specification for Design.

Patented Aug. 15, 1922.

Application filed December 6, 1921. Serial No. 520,452. Term of patent 3½ years.

To all whom it may concern:

Be it known that I, BARNET NEWLAND, a citizen of the United States, and a resident of the city of New York, in the county of New York and State of New York, have invented a new, original, and ornamental Design for Loops for Lighting Fixtures, of which the following is a specification, reference being had to the accompanying drawings, forming part hereof.

The figures of the drawing show the design of the article.

Fig. 1 is a front view and Fig. 2 a side view of a loop for lighting fixtures embodying my design.

I claim:

The ornamental design for a loop for lighting fixtures, as shown.

BARNET NEWLAND.
